HEAD REST FOR BASINS AND THE LIKE

William S. Rickard, Chicago, Ill.

Application March 5, 1938, Serial No. 194,044

1 Claim. (Cl. 4—159)

The present invention relates to improvements in head rests for basins and the like, and is directed particularly to a head rest designed for use in shampooing and washing hair that is adapted to be used particularly in homes, but which may be used with equal facility and with the same resultant advantages in ladies' hair dressing establishments and barber shops.

A primary object of the invention is to provide 10 a new and improved head rest having one surface upon which the back of the head is adapted to rest and a second surface having mounted thereon means adapted to secure the head rest to either flat or rounded surfaces of the rims of basins, wash bowls, bath tubs, or other fixtures.

A more specific object of the invention is to provide a new and improved head rest constructed of resilient non-metallic material having a pair of opposed surfaces spaced a substantial 20 distance apart, one of which is configured comfortably to receive the back of the head and the other to mount suction cups having at least an exterior surface of resilient non-metallic material thereby to provide a head rest that prevents 25 the head from contacting any metallic surfaces of fixtures upon which the head rest may be mounted or any metal that may be used in the construction of the head rest itself.

A head rest constructed in accordance with the 30 present invention has not only the advantage already enumerated, but has the additional advantage that it is extremely sanitary. This results primarily from the fact that it is adapted to be secured directly to either the flat or rounded 35 surfaces of the rims of such fixtures as a basin, wash bowl, bath tub, or the like. Consequently, after use it can be detached from the surface of the fixture and the surface, and likewise the head rest itself, can be readily cleansed. Furthermore, when the head rest is used by more 40 than one person, it can be covered, if desired, by towels or the like, which are replaced after use by an individual.

Another advantage resulting from providing a 45 head rest that is both readily attachable to and detachable from fixtures is that after use it can be stored in a cabinet or other out of the way place. Thus, it does not detract in any way from the appearance of either the fixture or the room in which it is used. This advantage is of importance 50 when the device is used in individual homes. However, in this connection, it may be noted that the head rest of the present invention may be constructed with a pleasing external

appearance so that it will not materially detract from appearances, no matter where attached.

The construction of the head rest and securing means with at least an exterior surface of non-metallic resilient material, such as rubber, also eliminates structural parts that are likely to rust after continued use and contact by water and other liquids.

Other objects and advantages of the present invention will become more apparent from the 10 ensuing description thereof in the course of which reference is had to the accompanying drawing, in which:

Fig. 1 is a perspective view showing the mode of attachment and use of the head rest of the 15 present invention; the head rest being shown installed upon a wash bowl provided with a rim having a substantially flat surface;

Fig. 2 is a perspective view showing the head rest mounted upon a bath tub constructed with 20 a rim having a rounded surface;

Fig. 3 is an enlarged side elevation of the head rest itself;

Fig. 4 is a bottom view of the head rest shown in Fig. 3, and

Fig. 5 is a cross-sectional view, taken along the line 5—5 of Fig. 3.

Referring first to Fig. 1, it may be seen that the head rest of the present invention, which is indicated generally by reference numeral 10, is 30 mounted directly upon the flat upper surface of the rim 12 of a wash bowl 14. When so mounted a relatively high stool 16 may be placed in front of the bowl to accommodate a person so that the back of the head may be placed upon 35 the upper surface of the support. When the person is so positioned, the hair may be both conveniently and easily washed, rinsed or otherwise treated. The back of the head and neck are kept a substantial distance from the bowl 40 surface, thereby eliminating the uncomfortable feeling arising from contact with its metallic surface.

The head rest may be mounted also upon rounded surfaces of fixtures as illustrated in Fig. 45 2, where the head rest 10 is shown mounted upon the rounded rim 20 of the bath tub 22. In this case the stool 24 should be made considerably lower than the stool 16, because of the relative heights of the rims of the two fixtures. While 50 no person has been illustrated in Fig. 2, it should be apparent that one may be seated upon the stool 24 with the back of the head resting upon the head rest 10, just as illustrated in Fig. 1. In order to provide a convenient source of water 55

for use in shampooing and rinsing the hair, it is preferable that a spray 26 attachable to the faucet be used.

The head rest 10 may be considered as consisting of two major parts, these being the relatively wide support 30 and the means 32 for securing the support to either flat or rounded surfaces of fixtures such as those illustrated in Figs. 1 and 2. The support 30 is made of some relatively resilient non-metallic material, such as rubber having a texture corresponding to that used in rubber heels and the like. The rubber should be of a grade not affected either by water or by the various materials used in shampooing the hair. Comfort to the user is provided not only by making the support 30 of rubber, but also by making the upper surface 34 thereof concave in configuration, as illustrated in Fig. 3.

20 In order to avoid, as far as possible, the likelihood of the body of the person contacting the metal of the fixture upon which the head rest is mounted, the thickness of the support is made substantial so as to provide a pair of opposed surfaces, the previously mentioned surface 34 and the bottom surface 36, that are spaced a substantial distance apart.

The securing means 32 of the head rest are so constructed that the head rest may be both easily 30 and simply attached to and detached from either the flat or rounded surfaces of the fixtures with which it is to be used. As may be noted particularly from Figs. 4 and 5, the securing means take the form of suction cups having concave inner 35 suction surfaces 38. These cups are constructed in accordance with usual manner from relatively resilient non-metallic material, preferably a grade of rubber that is somewhat softer than the rubber from which the head support 30 is made. 40 The cups may be secured to the support 30 in any known manner, as by means of brass screws 40 molded in the cups and adapted to be threaded into the under surface of the support. The cups 32 may be molded or otherwise secured directly to the head rest, but it is important, in so far as the present invention is concerned, that the exterior surfaces 42 thereof consist only of 45 resilient non-metallic material so as to eliminate all possibility of the user's body contacting any metal that may be used in securing the cup to the support. In the present embodiment it may be seen that this result is obtained by extending the upper end of the cup around the head 44 of the screw 40.

50 When it is desired to attach the head rest of the present invention to the flat surface of a basin, such as the flat rim 12 of a basin 14, it is necessary only to place the head rest upon the rim and apply a slight amount of pressure thereon. Thereafter the head rest is securely held in place by the suction principle which is well known to those skilled in the art and needs no further elaboration at this point. After the head rest has been used it may be removed in a manner that 55 is also well known to those skilled in the art and put away in some out of the way place, such as a cabinet. In use the head rest of the present invention provides a comfortable relatively soft support for the back of the head. The rub-

ber exterior of the head rest eliminates all possibility of the body of the person contacting any metal used in the construction of the head rest and the substantial distance between the opposed surfaces 34 and 36 eliminates practically 5 all possibility of the body of the person contacting any metal upon the fixture. A head rest constructed in accordance with the present invention also eliminates all metal surfaces that would be likely to become covered with rust after a long 10 period of use.

A distinct advantage of the head rest of the present invention resides, as stated above, in the fact that it can be applied to either flat or rounded surfaces. It is shown mounted upon 15 the rounded rim 20 of a bath tub in Fig. 2. While the rims of bath tubs such as illustrated are relatively wide, the head rest may be constructed for use with fixtures having somewhat narrower rims by making the suction cups 32 20 with somewhat smaller diameters.

The head rest can be used with practically any of the fixtures now commonly used either in homes or other establishments, such as ladies' hair dressing parlors and barber shops. It requires no alteration in the construction of the fixtures as now installed, nor does it require the fixtures to be constructed for the particular use for which they are intended. When the head rest is used in hair dressing establishments or barber 30 shops, it can be very easily covered by means of a small towel in order to make its use sanitary.

The embodiment of the invention that has been described above for the purpose of illustrating an embodiment of the invention may be modified 35 to meet various conditions of use. It has already been suggested that the size of the suction cups may be varied and it is contemplated that the proportions of the head support 30 may likewise be varied as desired. It is contemplated 40 further that the relative hardness of the rubber from which the support and suction cups are constructed may be varied and that the suction cups themselves may be secured to the support in various ways.

What I claim as new and desire to secure by United States Letters Patent is as follows:

A head rest adapted to be mounted in secure but readily detachable fashion upon relatively flat or rounded rims of wash bowls, bath tubs, and the like, including in combination, a substantially solid resilient support, said support being substantially liquid impervious throughout, relatively short, of a width comfortably to receive the back of the head, and provided with a pair of spaced apart opposed surfaces, one of said surfaces being concave so as comfortably to support the back of the head, and suction cups on the other of said surfaces for mounting the support upon the rim of the basin or the like in a secure but readily detachable fashion with the concave surface of the support facing away from the rim, said opposed surfaces being spaced apart a distance such that when the support is mounted in place, the concave surface is spaced from the surface of the rim a distance sufficient to prevent contact of the user's head with the rim.

WILLIAM S. RICKARD.
